UNITED STATES PATENT OFFICE.

GEORGE JOHN STEVENS, OF LONDON, ENGLAND, ASSIGNOR, BY MESNE ASSIGNMENTS, TO AMERICAN ATTACHMENT COMPANY, OF PORTLAND, MAINE, A CORPORATION OF MAINE.

COMBINED PRESSER-FOOT AND GUIDE FOR SEWING-MACHINES.

No. 902,180.

Specification of Letters Patent.

Patented Oct. 27, 1908.

Application filed February 6, 1902. Serial No. 92,883.

To all whom it may concern:

Be it known that I, GEORGE JOHN STEVENS, a subject of the King of Great Britain and Ireland, formerly of Bradford, county of 5 York, England, now residing at 25 East Lake road, Loughborough Junction, London, S.E., England, have invented a certain new and useful improvement in a combined presser-foot and guide for sewing-machines for producing blindstitching and fancy and ornamental stitching and the like, of which I declare the following to be a full, clear, and exact specification.

My invention relates to a combined presser-foot and guide for sewing machines for producing blind-stitching, while at the same time not interfering with the use of the machine for plain stitching, the object of my invention being to produce a device that shall 15 be of extreme simplicity in construction, and both easy and inexpensive to manufacture; easy to secure to and readily adjustable upon any ordinary sewing machine, and capable of use upon the same; that will perform the 20 work of blind-stitching, hemming, and the like, with the usual and ordinary lock-stitch of the machine, and that will perform this work upon substantially all kinds of material, however thick or thin they may be.

25 The novel construction, combination, and arrangement of parts constituting my invention will be hereinafter fully described, pointed out in the appended claims, and illustrated in the accompanying drawings, which 30 form a part of this specification, and in which:—

Figure 1 is a perspective view showing my combined presser-foot and guide in place upon a sewing machine, with a piece of work 35 folded and being stitched. Fig. 2, is a perspective view of the combined presser-foot and guide by itself, showing the presser-bar in dotted lines. Fig. 3 is a side elevation of the parts shown in Fig. 2, the inner foot being 40 depressed somewhat to form the guide. Fig. 45 is a view showing the bottom of the presser-foot and guide. Fig. 5 is a front cross sectional view of the same, and Fig. 6 is a plan view of the same showing the parts slightly 50 separated.

In carrying my invention into effect I provide a block A, which is so constructed as to be readily attached to the presser-bar B of the sewing machine by a suitable set-screw b 55 instead of the ordinary presser-foot. Upon

the outer side of this block A, which is provided with a rearwardly projecting extension A¹, I secure a presser-foot C, the inner side of which, that is to say the side next to the needle D, is cut away somewhat to form a 60 recess c, through which the needle D may pass.

To the opposite side of the block A, I secure another presser-foot E, provided with a recess e, on its outer face next the needle D. 65 I preferably construct the block A with the two vertical ribs a, a¹, located opposite to each other upon the rearwardly projecting extension A¹, and about midway of its length, and just back of the point of attachment to the 70 presser-bar B, and construct the two presser-feet C, E, with corresponding grooves or channels, c¹, e¹, permitting engagement with the ribs a, a¹, just mentioned. The two presser feet C, E, may be attached to the 75 block A with set screws c², e², or in any other desired way, that will permit of the necessary adjustment hereinafter mentioned.

I provide the two presser feet C, E, with vertical slots c³, e³, through which the set 80 screws c², e², that secure the presser feet C, E, to the block A may pass, permitting the presser feet C, E, to be adjusted up and down upon the block A, and to be secured in any desired position thereon. Back of the set 85 screws c², e², that secure the presser feet C, E, to the block A, I provide adjusting screws F, G, which pass through screw threaded holes f, g, in the presser feet C, E, and have their bearing against the adjacent face of the 90 rearwardly projecting extension A¹, of the block A.

In carrying my invention into operation upon machines where the work is fed from the operator toward the back of the machine, 95 the cloth H to be blind-stitched is folded as shown in Fig. 1, and placed under the outer presser foot C, the cloth I, to which the first piece H is to be blind-stitched, being beneath the folded piece and laid flat upon the 100 machine; or the two pieces of cloth H, I, to be joined, may both be folded separately and laid the one upon the other, both folds being placed under the outer presser foot C. The set-screw e² binding the inner presser-foot E 105 to the block A is then loosened, and the inner presser-foot E allowed to drop to near the bed-plate K of the machine, in which position it is then secured to the block A, by tightening the set-screw e².

The inner presser-foot E, in the construction above described, serves as a guide for the work, which is fed against it, the outer face of this presser foot E, that is, the face next the 5 needle D, being almost in line with the inner face of the needle D, that is to say, the face toward the arm of the machine, so that as the work is fed to the machine, and against the inner presser foot E, the needle D must pass 10 more or less exactly through the center of the fold of the cloth H and not entirely through its entire thickness, from side to side of the cloth.

By simply turning the adjusting screw G, 15 at the rear of the inner presser foot E, the one way or the other, the point of the presser-foot E may be moved more closely to, or away from the needle D, thus giving the adjustment necessary for sewing cloths of varying thicknesses. It will be obvious that 20 instead of making the inner presser foot E serve as the guide, that in cases where the work is fed from the back of the machine toward the operator, that the outer presser-foot C may be used as the guide, the work in 25 this case being fed against it from the other side. The presser foot C in this case will be lowered to near the bed-plate K of the machine, in order to serve as the guide, and secured in this position by the set-screw c^2 , 30 while the point of the foot C will be adjusted toward or away from the needle D, by turning the adjusting screw F the one way or the other. The work will then be folded and 35 placed under the foot E, which will serve as the presser-foot. Or, if preferred, the sewing machine may be provided with two presser-bars side by side, and the two presser-feet C, E, may be attached thereto, instead 40 of to the block A above described. As it is essential that the presser-foot that acts as the guide should lie so close to the needle D that the latter when making the stitch cannot 45 pass entirely through the thickness of the cloth operated upon, as otherwise the stitch would show upon both sides of the cloth, I construct the recesses c , e , in the faces of the presser-feet, just sufficiently large enough to take the bulge of the cloth as the needle 50 passes through it. If either too large or too small, irregular stitching will be the result.

In order that the feed of the machine, where an L shaped feed is used, may not rub against the presser foot E, and injure either 55 the foot or the feed, or cause vibrations that might effect the regularity of the stitching, I form a small recess e^4 in the bottom of this foot as is clearly shown in Fig. 4.

Having now fully described my invention, 60 what I claim as new and desire to secure by Letters Patent is:—

1. A blind stitching device for sewing ma-

chines, comprising a presser foot and a guide foot, rigidly attached to the presser bar and in different horizontal planes, said presser foot and said guide foot being laterally adjustable independently of each other, and each of said feet being vertically adjustable, whereby either of said feet may act as a presser foot. 65

2. In combination, two feet attached to a presser bar in different horizontal planes and one of them having a vertical recess in its edge to receive the bulge of the cloth and means for adjusting the said recessed foot 70 towards and from the needle, the said presser feet maintaining a permanent relation to each other when adjusted substantially as described.

3. In combination, two feet attached to 80 the presser bar, each being vertically and laterally adjustable independently of the other whereby each may be adjusted to a higher position in relation to the other and each may be adjusted towards the needle and 85 each having a vertical recess in its edge near the needle, substantially as described.

4. A blind-stitching device for sewing machines, comprising a block adapted to receive and be secured to the presser-bar of the 90 machine, a rearwardly projecting extension upon the said block, two feet secured to the extension of the block, and means for adjusting the said feet vertically upon the said extension said means serving to fix the said 95 presser feet rigidly in position.

5. A blind-stitching device for sewing machines, comprising a block adapted to receive and be secured to the presser-bar of the machine, a rearwardly projecting extension 100 upon the said block, two feet secured to the extension of the block, means for adjusting the said feet vertically upon the said extension, and means for adjusting the said feet nearer to or away from each other and the 105 needle of the machine said means serving to fix the said presser feet rigidly in position.

6. A blind-stitching device for sewing machines, comprising a block adapted to receive and be secured to the presser-bar of the 110 machine, a rearwardly projecting extension upon the said block, vertical ribs upon the said extension, and two feet adjustably secured to the said extension with means for fixing the presser feet rigidly in position, and having grooves or channels for engagement with the said ribs. 115

In witness whereof I have hereunto set my hand in presence of two witnesses.

GEORGE JOHN STEVENS.
